UNITED STATES PATENT OFFICE.

HENRY PORTER DAVIS, OF WASHINGTON, DISTRICT OF COLUMBIA.

DENTAL GOLD-PELLET HOLDER.

No. 844,781.

Specification of Letters Patent.

Patented Feb. 19, 1907.

Application filed April 23, 1906. Serial No. 313,101.

To all whom it may concern:

Be it known that I, HENRY PORTER DAVIS, a citizen of the United States, residing at Washington, in the District of Columbia, 5 have invented new and useful Improvements in Dental Gold - Pellet Holders, of which the following is a specification.

My invention relates to new and useful improvements in dental apparatus for facilitating the operation of filling teeth with gold; and its particular object is to provide an instrument specially adapted to hold the annealed gold in a compact and accessible way, ready to the hand of the operator. In 15 order to carry out this object, I have devised the construction and arrangement of parts illustrated in the accompanying drawings, wherein—

Figure 1 represents a general side view of 20 my dental gold-pellet holder in its closed position. Fig. 2 represents a top view of the same with the gold-carrying spindle withdrawn, and Fig. 3 represents said gold-carrying spindle.

25 In the process of filling decayed teeth with gold it is the usual custom to have the gold in small pieces, in a suitable soft or spongy form, and to anneal it shortly before it is used by holding it in a flame for a moment.

30 The bits of gold, usually in pellet or cylindrical form, according to the general practice, are placed in the cavity one at a time and condensed with a plunger or the like.

35 In some cases a holder or magazine for feeding the gold into the tooth is used. This holder being held by the operator in one hand leaves his other hand free to work with. My improved device is of this character.

Referring now to the drawings, A is a metallic tube having the narrow opening or slot B along one side, as shown in Fig. 2. At the forward end the tube is cut away so as to form three spring-like prongs C C C. I may also provide this end of the tube with a plunger D, as shown, though this is not really essential. At the rear end the tube terminates in a ferrule E.

F is a metallic spindle of approximately the same length as the tube and designed to 40 be contained by it. This spindle terminates at the rear end in a convenient handle G. H H, &c., are the pellets or cylinders of gold, which are strung on the spindle F.

The various parts of my invention being constructed and arranged as described, its mode of operation is as follows: When it is 55 desired to fill a cavity, I provide one or more spindles loaded with gold cylinders, as shown. I then anneal the gold at one operation and insert the spindle, with the gold strung 60 on it, in the tube. A slight shake of the tube when held upright will now bring one of the cylinders down the spindle till it is held lightly by the retaining-prongs C, whereupon it is readily withdrawn from the tube 65 by the plunger or other instrument held in the other hand and placed in the cavity. When this cylinder had been compressed in the cavity, another one is brought down and treated in the same way. If a cylinder 70 happens to stick in the tube, it is easily dislodged by running a plunger or the like along the slot B. The plunger D may be used to aid in compressing the gold in the cavity, if desired. The holders can of course be made in various 75 sizes to suit different sizes of gold cylinders. It is possible to use the holder without the spindle, the holder in that case being simply loaded with the gold pellets or cylinders, which are shaken down as needed or poked 80 down through the slot. The spindle is a useful feature, however, as it enables the operator to anneal a number of pellets at one time.

Having thus described my invention, what 85 I claim, and desire to secure by Letters Patent, is—

1. A holder for dental-gold pellets consisting of a longitudinally-slotted tube adapted to receive the gold, and means at the lower end 90 of the tube for loosely retaining the gold in the tube.

2. A holder for dental-gold pellets consisting of a tube A provided with a longitudinal slot B, open at the forward end, and with 95 spring-like retaining-prongs C at said forward end, and a spindle F for carrying the gold pellets, adapted to be contained within the tube.

In testimony whereof I have signed my 100 name to this specification in the presence of two subscribing witnesses.

HENRY PORTER DAVIS.
